UNITED STATES PATENT OFFICE

HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

MINE-LAYING SUBMARINE

Application filed June 3, 1929. Serial No. 367,934.

This invention relates to mine laying submarine boats, and more particularly to a submarine boat for laying mines by what is known as the dry system.

One of the main objects of my invention is to provide a submarine boat having mine stowage tubes so disposed as not to occupy valuable space in the pressure hull, these tubes having associated therewith means for transferring the mines from the tubes and for discharging them exteriorly of the hull. Another object is to so dispose the mine stowage tubes in relation to the hull structure as to obviate any increase in the dimensions thereof, thus preventing interference with the speed or radius of action of the boat. A further object is to provide a boat in which the stowage tubes and associated parts are so disposed as to provide an extremely simple compensating system while also preventing any material change in trim of the boat during discharge of the mines.

Still another object is to so dispose the mine stowage tubes as to enhance the stability of the boat and reduce likelihood of the mines in the tubes being struck in the event of collision when the boat is running afloat. It is also an object of my invention to provide simple and highly efficient means for laying or discharging the mines while permitting the same to be examined immediately before discharge to determine the condition of the gear thereof. Further objects and advantages of my invention will appear from the detailed description.

In the drawings:

Figure 1 is a fragmentary horizontal sectional view taken through the mid-ship portion of a submarine boat constructed in accordance with my invention;

Figure 2 is a fragmentary vertical sectional view through the mid-ship portion of the boat;

Figure 3 is a section taken substantially on line 3—3 of Figure 2;

Figure 4 is a section taken substantially on line 4—4 of Figure 2;

Figure 5 is a section taken substantially on line 5—5 of Figure 2;

Figure 6 is a section taken substantially on line 6—6 of Figure 2;

Figure 7 is a detail, on an enlarged scale, of the means for operating the spoon.

The boat is, in general, of known construction and comprises an inner pressure hull 1 and an outer hull 2, the space between these two hulls constituting ballast, fuel and compensating tanks in a known manner. I provide two mine stowage tubes 3 at the bottom of the boat. These tubes extend fore and aft of the hulls and are disposed at opposite sides of and equi-distant from the keel line. The tubes 3 are water-tight and are adapted to withstand full submergence pressure. The forward ends of the tubes are closed at 4. At their rearward ends the tubes open into spaces 5 which constitute downward extensions of a mine room 6 within hull 1 at the mid-ship portion thereof. Mine racks 7 are mounted in spaces 5 and, when the mines have been loaded into the tubes and upon these racks, removable stanchions 8 are secured at the top of the spaces 5 as in Figure 5.

The stowage tubes 3 open aft, that is, toward the stern of the boat. A mine transfer tube 9 is provided in alignment with each of the tubes 3 and adjacent racks 7, this transfer tube being disposed between the hulls. The transfer tube 9 is provided, at each end, with a gate valve 10. These valves operate in casings 11 which extend through the pressure hull 1 and into the mine room 6. Valves 10 may be operated manually from within the mine room 6, though I prefer to provide suitable mechanism for assuring quick operation of the valves, this mechanism comprising cylinders 12 to which compressed air may be supplied in a known manner, and mechanism operating in the cylinders and having operating connections with the valves.

Any other suitable or preferred means may be employed for operating the gate valves. The tube 9 and the associated valves constitute a lock for transferring a mine from the rack to the exterior of hull 1.

The aft end of tube 9 opens into a space 13 in which is mounted a cylindrical mine receiving and discharge spoon 14 which is 100

open at both ends. This spoon is pivotally mounted at the lower portion of its forward end, at 15 and, when in its normal raised position is disposed adjacent and in alignment with the transfer tube or lock 9.

5 Any suitable or preferred means may be provided for operating spoon 14. I have illustrated operating means comprising a cylinder 16 in which operates a piston to which is secured a piston rod 17 to the outer end of which is pivoted a yoke 18. The arms of this yoke extend forwardly along spoon 14, when the spoon is raised, and are pivotally secured at their forward ends at 19, to the upper ends of a pair of arms 20 which are pivotally mounted at their lower ends, at 21, in space or compartment 13 adjacent the sides thereof. A strap 22 is secured about the upper portion of spoon 14, centrally thereof, and pins 23 are secured in the ends of this strap and operate in slots 24 in arms 20 and extending lengthwise thereof. Suitable means is provided for admitting liquid under pressure to the cylinder at either side of the piston for operating the spoon.

Preferably, though not necessarily, I provide a contact member 25 adjacent the aft end of the spoon and disposed for engagement by the end of a mine which has been moved into full position in the spoon. This contact member has associated therewith suitable means, either electrical or mechanical, for opening a valve and admitting liquid under pressure into the cylinder 16 at the inner side of the piston, when the mine is fully positioned upon the spoon. This results in outward movement of the piston rod 17 thus swinging the spoon downwardly about axis 15 into the dotted line position of Figure 2 so as to discharge the mine therefrom sternward and below the hull, as indicated. After the mine has thus been discharged, liquid under pressure is admitted to the cylinder at the outer side of the piston thus retracting the piston rod 17 and returning the spoon 14 to its inner normal or mine receiving position shown in full lines in Figure 2.

Each of the tubes 3 and the racks and locks 9 associated therewith, as well as the spoon 14, is provided with suitable conveying mechanism for moving the mines through the tubes in either direction and for transferring the mines from the racks to tube 9 of the lock. This conveying mechanism also serves to move the mines outwardly of the lock into proper position in the spoon 14 to be discharged thereby. Conveying mechanism of this character is known in the art and need not be illustrated nor described in detail. 60 I have indicated such mechanism diagrammatically in Figure 2 by pinions 26 disposed in the upper portion of tube 3, lock 9 and spoon 14, and above racks 7.

These pinions are driven in a known manner by an electric motor 27 disposed in the

mine room 6. Operation of this motor and of any selected set of the pinions 26 is controlled in a manner well known in the art. The conveyor mechanism provides means whereby the mines can be loaded into the stowage tubes and can be transferred therefrom to the mine receiving and discharge spoon with facility.

When it is desired to lay or discharge the mines, the valve at the forward end of the tube or lock 9 is opened, the other valve remaining closed. A mine is then moved from the rack into lock 9 and the valve at the forward end of this lock is then closed. The water is then admitted to lock 9, in a known manner, from a compensating tank 28 (Figure 4) disposed between the two locks and in alignment therewith transversely of the hull structure. This compensating tank may be otherwise disposed, but is conveniently disposed as illustrated. The valve at the aft end of lock 9 is then opened and the mine is moved aft into the spoon 14 and, when in full position upon the spoon, contacts member 25 causing the spoon to be swung downwardly about its pivot 15 into the dotted line position of Figure 2 so as to discharge the mine therefrom. To permit of this operation of the spoon and discharge of the mine, outer hull 2 is provided with a suitable opening through the bottom thereof and, when the spoon is in raised position, this opening is covered by a plate 29 secured to the lower portion of the spoon, this plate conforming in curvature to the outer hull and the hull being faired to the plate.

This is advantageous as avoiding projections or openings in the outer hull such as would interfere with ready passage of the boat through the water and consequently reduce the speed or radius of action thereof.

Water is transferred from supplemental compensating tank 28 to a main compensating tank 30 disposed immediately aft of spoon 14, this transfer of water from tank 28 to tank 30 being effected in a known manner. During the movement of the mine from lock 9 into the spoon 14, water is caused to flow from compensating tank 30 forwardly to a second main compensating tank 31 disposed immediately forward of the forward end of tube 4, in a known manner. This forward movement of the water offsets the moment due to the rearward or sternward movement of the mine.

I preferably provide a quick flooding compensating tank 32 disposed in alignment with spoon 14 transversely of the hull structure. This tank 32, like tank 28, may conveniently be disposed mid-way between the spoons, that is, in vertical alignment with the keel 33 and between the inner and outer hulls, as illustrated in Figure 3. The tank 32 has a capacity such that the weight of the sea water taken into this tank equals the negative buoyancy of

8 a mine discharged from spoon 14. This tank is quickly flooded by means of a sea valve, during discharge of the mine from the spoon, and the sea valve is then immediately closed and the water is transferred to the main compensating tank 30 in a known manner thus leaving the tank 32 available for use when a second mine is discharged.

10 This tank 32 is of value in maintaining the trim of the boat and the tanks 32 and 28 are so disposed relative to the main compensating tanks 30 and 31 as to provide an extremely simple and highly efficient compensating system whereby the trim and stability of the boat 15 is readily maintained during laying of the mines.

15 As soon as a mine has been moved out of transfer tube or lock 9 into spoon 14, the valve at the aft end of the lock is closed and the 20 water in the lock is blown into the compensating tank 28 from which it is transferred to main compensating tank 30 as above set forth. The lock 9 is then in condition to receive a second mine which is transferred therethrough 25 to spoon 14 and discharged in the manner described, this operation being repeated until all, or as many as desired, of the mines have been discharged. In practice, the mines are 30 discharged from the tubes alternately so as to maintain the proper trim and stability of the boat. Admission of water from the supplemental compensating tank 28 to locks 9 may be controlled by a suitable valve 34 disposed in a pipe 35 establishing communication 35 between the locks and the tank. After all of the mines have been discharged, the compensating tanks 30 and 31 are preferably full of water, these tanks being of proper capacity to compensate for the mines. It is 40 to be particularly noted that the tubes, as well as the compensating tanks and associated parts, are disposed at the mid-ship portion of the boat.

45 This greatly facilitates compensation and enhances the trim and stability of the boat. In this connection, it is to be noted that the stowage tubes 3 are disposed at the bottom of the boat. This has the advantage of increasing the stability of the boat. While I have 50 shown two tubes disposed at opposite sides of and equi-distant from the keel line of the boat, I do not intend to in any way limit my invention to this number of tubes since the number of tubes used will depend largely 55 upon requirements and may be increased or diminished as required to meet given conditions. A further advantage of having the tubes at the lower portion of the hull structure is that, in the event of collision when the boat is running afloat, danger of the mines in the tubes being struck, with possible disastrous results, is largely eliminated.

60 Referring more particularly to Figure 2, it will be noted that the mine is discharged 55 downwardly through the bottom of the hull

and sternward so as to eliminate possibility of the mine fouling the hull. This discharge of the mine is facilitated by the forward travel of the boat and the mine sinks quickly to the bottom so as to clear the propellers in the continued forward travel of the boat, the mine rising after a predetermined interval of time, amply sufficient for the boat to pass well beyond the mine, and being thereafter maintained at a predetermined depth in the water, this being effected by known control mechanism associated with the mine.

70 While I prefer to dispose the mine stowage tubes at the bottom of the hull, or closely adjacent thereto, I do not limit myself to this arrangement under all conditions since the means for discharging the mines downwardly through the hull can be employed to advantage with stowage tubes disposed above the bottom of the boat. Under ordinary conditions, however, I prefer to dispose the stowage tubes and the discharge means in 75 the manner illustrated.

80 A hatch 34, provided with a suitable hatch cover or door 35, admits of the mines being lowered into the mine room 6 as indicated in Figure 2. After the mines have been lowered into the mine room, the stanchions 8 being removed, they are transported by a suitable trolley, which travels on rails 36 extending 85 transversely of the mine room and at opposite sides of hatch 34, to the racks 7. The mines are then loaded on to the racks and, by proper operation of the conveying mechanism, are moved forwardly into the tubes 3. After 90 the tubes have been loaded one mine is placed upon each of the racks. In this manner the tubes and the racks can be loaded with facility.

95 Each of the tubes 3 is capable of containing 100 nine mines which, with the one mine supported upon the racks in alignment with the tube, makes a total of twenty mines which can be carried by the boat. The length of the tubes can be varied within limits, however, and I do not, therefore, limit myself to 105 the particular number of mines which the tube carries.

110 By disposing the tubes between the hulls, valuable space within the pressure hull is not taken up and the necessity of increasing the dimensions of the boat to accommodate the mine stowage tubes is eliminated. It is also 115 to be noted that, by employing a small number of mine stowage tubes, the mines can readily be laid or discharged therefrom by comparatively simple mechanism and all necessity of employing a large number of discharging mechanisms for this purpose is 120 avoided.

125 A further advantage is that all of the mechanisms for transferring the mines from the tubes and for discharging them, are controlled from the mine room 6. The advantage of having the tubes 3 open into the spaces 130

or extensions 5 of the mine room is that the mines can be inspected immediately before discharge thereof to determine the condition of the mine gear and, if necessary, proper alterations or repairs therein can be made.

5. What I claim is:

1. In a mine laying submarine boat, a mine stowage tube at the bottom of the hull, a mine receiving and discharge spoon operating through the hull bottom, means for transferring mines from the tube to the spoon, and means for operating said spoon.

10. 2. In a mine laying submarine boat comprising an inner hull and an outer hull, a mine stowage tube disposed at the bottom of the boat between the hulls, a mine receiving and discharge spoon disposed between the hulls and operating through the bottom of the outer hull, means for transferring mines from the tube to the spoon, and means for operating said spoon.

15. 3. In a mine laying submarine boat comprising an inner hull and an outer hull, a mine stowage tube at the bottom of the boat and disposed fore and aft and between the hulls, and means for discharging mines from the tube through the bottom of the outer hull.

20. 4. In a mine laying submarine boat comprising an inner hull and an outer hull, two mine stowage tubes at the bottom of the boat and at opposite sides of and equidistant from the keel line, said tubes being disposed fore and aft and between the hulls, and means for discharging mines from the tubes through the bottom of the outer hull.

25. 5. In a mine laying submarine boat comprising an inner hull and an outer hull, a mine stowage tube disposed fore and aft and between the hulls, a mine receiving and discharge spoon disposed between the hulls and aft of and in alignment with the tube, means for transferring mines from the tube to the spoon, said spoon operating through the bottom of the outer hull, and means for operating said spoon.

30. 45. 6. In a mine laying submarine boat comprising an inner hull and an outer hull, a mine stowage tube disposed fore and aft and between the hulls, a mine receiving and discharge spoon aft of the tube and pivoted at its forward end for movement into mine receiving and mine discharging positions, the outer hull having an opening disposed to accommodate discharge of mines from the spoon, means for transferring mines from the tube to the spoon, and means for operating said spoon.

35. 50. 60. 7. In a mine laying submarine boat comprising an inner hull and an outer hull, a mine stowage tube disposed fore and aft and between the hulls at the bottom thereof, a mine receiving and discharge spoon aft of the tube and pivoted at its forward end for swinging movement upwardly and downwardly into mine receiving and mine dis-

charging positions, the outer hull having an opening accommodating movement of the spoon and discharge of mines therefrom, means for operating said spoon, and means for transferring mines from the tube to the spoon.

70. 8. In a mine laying submarine boat comprising an inner hull and an outer hull, a mine stowage tube disposed fore and aft and between the hulls at the bottom thereof, a mine receiving and discharge spoon aft of the tube and pivoted at its forward end for swinging movement upwardly and downwardly into mine receiving and mine discharging positions, the outer hull having an opening accommodating movement of the spoon and discharge of mines therefrom, means for operating said spoon, and means for transferring mines from the tube to the spoon, said operating means being controlled by positioning of a mine on the spoon.

75. 9. In a mine laying submarine boat comprising an inner hull and an outer hull, a mine stowage tube disposed fore and aft and between the hulls at the bottom thereof, a mine receiving and discharge spoon aft of the tube and pivoted at its forward end for swinging movement upwardly and downwardly into mine receiving and mine discharging positions, said spoon being aligned with the tube, means for transferring mines endwise from the tube to the spoon, the outer hull having an opening accommodating movement of the spoon and discharge of the mines from the spoon, and means for operating said spoon.

80. 10. In a mine laying submarine boat, a mine stowage tube disposed fore and aft of the hull, and at the midship portion thereof, mine receiving and discharge means, means for transferring mines from the tube to the receiving and discharge means, main compensating tanks forward of the tube and aft of the receiving and discharge means, a supplemental compensating tank, and a quick flooding supplemental tank adjacent the mine receiving and discharge means and having a seawater capacity approximately equal to the negative buoyancy of a mine.

85. 11. In a mine laying submarine boat, a mine stowage tube disposed fore and aft of the hull and at the midship portion thereof, mine receiving and discharge means adjacent the aft end of the tube, means for transferring mines from the tube to said receiving and discharge means, and a quick flooding compensating tank disposed in substantial alignment transversely of the hull with the receiving and discharge means, said tank having a seawater capacity approximately equal to the negative buoyancy of a mine.

90. In witness whereof, I hereunto subscribe my name this 28 day of May, 1929.

HUGO E. GRIESHABER.
